UNITED STATES PATENT OFFICE.

FERDINAND K. SVENSON, OF DETROIT, MICHIGAN.

PNEUMATIC WHEEL.

Application filed May 28, 1926. Serial No. 112,309.

This invention relates to a pneumatic wheel and has for its object to provide a wheel of such class in the manner as herein-after set forth, possessing the same cushioning function as the type of pneumatic tired wheel now in general use and further reducing the possibility of punctures and blow-outs to a minimum.

Further objects of the invention are to provide, in a manner as hereinafter set forth a pneumatic wheel which is simple in its construction and arrangement, strong, durable, thoroughly efficient in its use, readily assembled, and comparatively inexpensive to manufacture.

With the foregoing and other objects in view, the invention consists of the novel construction, combination and arrangement of parts as hereinafter more specifically described, and illustrated in the accompanying drawings wherein is shown an embodiment of the invention, but it is to be understood that changes, variations and modifications can be resorted to which fall within the scope of the claims hereunto appended.

In the drawings wherein like reference characters denote corresponding parts throughout the several views:—

Figure 1 is a side elevation of a pneumatic wheel in accordance with this invention.

Figure 2 is a section on line 2—2 Figure 1.

Figure 3 is a section on line 3—3, Figure 1.

Figure 4 is a section through a clamping member on line 4—4 Figure 1.

Figure 5 is a section through a clamping member on line 5—5 Figure 1.

Referring to the drawings in detail 1 denotes the hub of a wheel and which is provided with an annular peripheral flange 2 and opposing the latter, as well as being spaced therefrom is a flat clamping ring 3.

Mounted on the hub 1 and interposed between the flange 2 and plate 3 is an annulus 4. The annulus 4 is fixedly secured to the flange 2 and plate 3 by a series of hold fast devices 5. The annulus 4 is of appropriate diameter but it is obvious that it can be removed and a series of spokes substi-

tuted. Preferably the construction of the wheel is set up with the annulus 4.

Surrounding and spaced from the annulus 4 as well as being coupled therewith, is a pneumatic cushioning element consisting of an inner tube 7 which is enclosed by a shoe 8 of the split type and which is formed at its inner side with a pair of flanges 9, 10, interengaging with each other at their inner faces whereby when the flanges 9 and 10 are in abutting relation in cross section, a rectangular body will be provided. The outer side of the shoe 8 is formed with a circumferentially extending rib 11, of rectangular cross section and which corresponds in contour to the flanges 9 and 10 when they are in abutting relation. At the point of joinder of the flange 9, as well as the flange 10, with the body portion 8 of the shoe, each of said flanges is in-cut as at 12 to provide an annular groove. Each side of the rib 11 at the point of joinder thereof with the body portion of the shoe is in-cut as at 13 to provide an annular groove. The shoe 8 completely encloses the inner tube 7 and connected to the latter and extending through the flange 9 is a valved air filling tube 14 of any suitable form, but of a length to project a substantial distance from said flange 9, see Figure 3.

Surrounding and spaced from the pneumatic cushioning element, as well as being coupled therewith, is a resilient tire member 15.

The pneumatic cushioning element is coupled with the annulus 4 by a pair of oppositely disposed annular clamping members referred to generally by the reference characters 16 and 17. The clamping members 16 and 17 are constructed alike, with this exception that the clamping member 17 is formed with a slot 18 for the passage of the air valve element 14, see Figure 3.

In vertical section, each of the clamping members consists of a vertical portion 20, which is termed the intermediate part thereof, and an inner and an outer angle shaped portion 21, 22, respectively. The portion 21 is of greater length than the portion 22. The flanges of the outer portion 21 are indicated at 23, 24 and those of the inner

portion 22, at 25, 26. The flange 24 is inturned to provide a clamping nose 27. When the clamping members 16 and 17 are mounted in position, the outer portions 21 thereof abut against the flanges 9, 10 and the noses 27 of the flanges 24 engage in the grooves 12 and the inner portions 22 abut against the annulus 4 and extend against both sides thereof. The intermediate parts 20 of the clamping members 16 and 17 are secured together by hold fast devices 28 and the flanges 26 of the inner portions 22 are secured to the annulus 4 by the hold fast devices 29. The hold fast devices 28 and 29 detachably secure the clamping members 16 and 17 in position with respect to the annulus 4 and pneumatic cushioning element.

The tire 15 is connected or coupled with the pneumatic cushioning element by a pair of oppositely extending annular clamping members 30, 31. As each of the clamping members 30, 31 is of the same construction, the description of one will apply to the other. Each clamping member comprises an intermediate portion 32, and an outer and an inner portion 33, 34 respectively of angle shaped cross section. The outer portion 33 consists of a pair of flanges 35, 36 disposed at right angles with respect to each other and the inner portion 34 consists of a pair of flanges 37, 38 disposed at right angles with respect to each other. The flanges 38 of each inner portion 34 are inturned as at 39 to provide a clamping nose. The noses engage in the grooves 13 of the rib 11. The intermediate portions 32 of the clamping members 30, 31 are detachably connected together by hold fast devices 40. When the clamping members are arranged in coupling position with respect to the tire 15 and pneumatic cushioning element, the outer portions 33 abut against the tire 15 and also bear against the sides thereof. The inner portions 34 abut against the rib 11 and bear against the sides thereof and further extend into the grooves 13. The engaging of the noses 27 and 39 in the grooves 12 and 13 respectively connect the two pair of clamping members with the pneumatic cushioning element.

Each of the outer clamping members is formed throughout with spaced reinforcing ribs. Certain of the ribs extend from an inner portion of a clamping member and the other of the ribs extend from the outer portion of the clamping member. The ribs extending from the inner portion of the clamping member are alternately disposed with respect to the ribs which extend from the outer portion of the clamping member. The ribs are of slightly less length than the length in vertical section of the intermediate part of the clamping member. The ribs which extend from the inner portion of a clamping member are indicated at 41

and those that extend from an outer portion of the clamping member are indicated at 42. The ribs are formed on the outer side of the clamping member. The ribs are rounded in sectional plan, as indicated at 43 in Figure 5. In Figure 4 one of the ribs is illustrated and is shown as extended from the inner portion of a clamping member. The ribs are disposed in pairs between each pair of hold fast devices 40 and the ribs of each pair are spaced from each other. One of the ribs of the pair extends from inner portion of the clamping member and the other of the pair extends from the outer portion of the clamping member.

The inner clamping members are provided with ribs 44 on the intermediate portions thereof. The ribs 44 are not arranged in pairs as the ribs formed on the outer clamping members. The ribs 44 extend from the outer portions towards the inner portions of the inner clamping members. The ribs 44 are of the same form as the ribs 42.

The two pair of clamping members will hold the tire member 15 and pneumatic cushioning element firmly and will prevent any water or moisture from coming in contact with the inner tube 7. Under such conditions the life of the inner tube 7 of the pneumatic cushioning element is materially increased. By positioning the tire member 15 exteriorly with respect to the pneumatic cushioning element, as well as spacing the tire member 15 from said element, the pneumatic cushioning element is always supported above the ground thereby preventing wear and also prevents the pneumatic cushioning element from coming in contact with obstructions or any obstacle which may injure the same.

It is thought the many advantages of a pneumatic wheel, in accordance with this invention, can be readily understood, and although the preferred embodiment of the invention is as illustrated and described, yet it is to be understood that changes in the details of construction can be had which will fall within the scope of the invention as claimed.

What I claim is:

1. A pneumatic wheel comprising a felloe, a pneumatic cushioning element surrounding and spaced from said felloe, a tire member surrounding and spaced from said element, a pair of oppositely disposed clamping members having binding engagement with said tire member and element for maintaining them in spaced relation, and a pair of clamping members having binding engagement with said element and secured to said felloe for maintaining the element and felloe in spaced relation, each of said clamping members formed with an intermediate ribbed part.

2. A pneumatic wheel comprising a tire member, a pneumatic cushioning element surrounded by and spaced from said tire member, a pair of oppositely disposed 5 clamping members each including a pair of angle shaped in cross section outer and inner portions, said portions clamping against said member and element for connecting them together and for maintaining them in spaced relation, a pair of oppositely disposed clamping members having binding engagement with said element, means for connecting the second mentioned pair of clamping elements with the hub of a wheel, and each 10 of said clamping members further including an intermediate part inset with respect to the outer and inner portions thereof and provided with reinforcing ribs.

3. A pneumatic wheel comprising a tire member, a pneumatic cushioning element, a 20 pair of oppositely disposed clamping members carrying said tire member and inter-engaging said cushioning element, said clamping members provided with inset intermediate portions opposing each other for maintaining said tire member and cushioning element in spaced relation, means engaging 25 with said intermediate portions for securing said clamping members together and for binding them against said tire member and cushioning element, a pair of oppositely disposed clamping members, means for securing 30 said last mentioned pair of clamping members with the hub of a wheel, said last mentioned pair of clamping members engaging 35 said cushioning element and provided with inset intermediate portions opposing each other for maintaining said cushioning element in spaced relation with respect to 40 the hub of a wheel, and means engaging with the intermediate portions of said second mentioned pair of clamping members for maintaining them in clamping engagement with respect to said cushioning element.

4. A pneumatic wheel comprising a tire member, a pneumatic cushioning element surrounded by and spaced from said tire member, an inner and an outer pair of 50 clamping members, the members of each pair being oppositely disposed and each of said members including an inset intermediate part provided with an inner and an outer laterally disposed angle-shaped in cross section portion, the angle-shaped portions of the outer pair of clamping members clamping against said tire member and element for connecting them together and with the intermediate parts of said outer pair of clamping members maintaining said tire member and element in spaced relation, the outer angle-shaped portions of the inner pair of clamping members clamping against said element, means for securing the inner angle-shaped portions of the inner pair of clamp-

ing members with the hub of a wheel, the intermediate parts of said inner pair of clamping members maintaining said element in spaced relation with respect to the hub of the wheel, means for securing the intermediate parts of the outer pair of clamping members together to maintain the same in clamping engagement with respect to said tire member and element, and means for securing the intermediate parts of the inner 50 pair of clamping members together to maintain said members in clamping engagement with respect to said cushioning element.

5. A pneumatic wheel comprising a tire member, a pneumatic cushioning element 80 surrounded by and spaced from said tire member and provided at its outer and inner portions with a peripherally arranged circumferentially extending rib coextensive therewith, said element further formed with 85 a circumferentially extending groove at each side of the base of each of said ribs, a pair of oppositely disposed outer clamping members for connecting said tire member to said element, said clamping members overlapping the rib at the outer portion of said element and extending in the grooves at the base of said rib, a pair of oppositely disposed inner clamping members overlapping 90 the rib at the inner portion of said element and extending into the grooves at the base of such rib, means for securing said inner pair of clamping members with the hub of the wheel, said outer clamping members including inset intermediate parts for 95 maintaining the tire member in spaced relation with respect to said element, and said inner pair of clamping members provided with inset intermediate parts for maintaining 100 said element in spaced relation with respect to said hub.

6. A pneumatic wheel comprising a tire member, a pneumatic cushioning element surrounded by and spaced from said tire member and provided at its outer and inner 110 portions with a peripherally arranged circumferentially extending rib coextensive therewith, said element further formed with a circumferentially extending groove at each side of the base of each of said ribs, a pair 115 of oppositely disposed outer clamping members for connecting said tire member to said element, said clamping members overlapping the rib at the outer portion of said element and extending in the grooves at the base of said rib, a pair of oppositely disposed inner clamping members overlapping the rib at the inner portion of said element and extending into the grooves at the base of such rib, means for securing said inner pair of 120 clamping members with the hub of the wheel, said outer clamping members including inset intermediate parts for maintaining the tire member in spaced relation with respect to said element, said inner pair of 125 clamping members with the hub of the wheel, said outer clamping members including inset intermediate parts for maintaining the tire member in spaced relation with respect to said element, said inner pair of 130

clamping members provided with inset intermediate parts for maintaining said element in spaced relation with respect to said hub, means engaging with the intermediate inset parts of said outer clamping members for maintaining these latter in clamping engagement with respect to the tire member and

element, and means engaging with the inset intermediate parts of the inner clamping members for maintaining these latter in engagement with said element. 10

In testimony whereof, I affix my signature hereto.

FERDINAND K. SVENSON.
